COMBINED CHAIR, HAIR DRYER AND TELEVISION VIEWER

Reid S. Larsen, 4436 Illinois Ave.,
Fair Oaks, Calif. 95628

Filed Apr. 15, 1969, Ser. No. 16,749

Term of patent 14 years

Int. Cl. D6—01

U.S. Cl. D15—1

FIG. 1

FIG. 3

FIG. 2

FIG. 4

FIG. 5

FIG. 1 is a side perspective view of my new design for a combined chair, hair dryer and television viewer;

FIG. 2 is a reduced side elevational view from the opposite side thereof;

FIG. 3 is a reduced rear elevational view;

FIG. 4 is a reduced front elevational view thereof; and

FIG. 5 is a reduced top plan view thereof.

I claim:

The ornamental design for a combined chair, hair dryer and television viewer, substantially as shown.
